UNITED STATES PATENT OFFICE.

LEWIS C. BAYLES AND FRED M. SLATER, OF EASTON, PENNSYLVANIA, ASSIGNEES TO INGERSOLL-RAND COMPANY, OF JERSEY CITY, NEW JERSEY, A CORPORATION OF NEW JERSEY.

DISK VALVE FOR ROCK DRILLS.

Application filed May 27, 1925. Serial No. 33,118.

This invention relates to fluid actuated rock drills, but more particularly to an improved oscillating disk valve construction capable of ready and convenient application to a rock drill having automatic rotation for the drill steel.

The objects of the invention are to enable an oscillating disk valve to be located rearwardly of the cylinder and around the rifle bar of the rock drill, in such location that the length of the drill is not increased and no material weight is added to the drill.

The invention is illustrated in one of its preferred forms in the accompanying drawings, in which—

Figure 1 is a longitudinal sectional elevation of a rock drill partly broken away showing the invention,

Figure 2 is a transverse sectional view on the line 2—2 of Figure 1 looking upwardly in the direction of the arrows, the ports Y and Z underneath the valve being shown in dot and dash lines to indicate their shape and to show that they are in front of the section taken and are present in the construction but are not actually seen in Figure 2, and

Figure 3 is a detail transverse sectional view through the valve.

Referring to the drawings, the cylinder A is provided with the reciprocating piston B having the forward extension C extending through the front head washer D. The piston is provided with the usual rifle nut E cooperating with the rifle bar F for imparting rotation to the drill steel, which, together with the front head and chuck parts are not shown for purposes of simplicity. The usual water tube G extends through the rifle bar and piston, and the rifle bar is provided with the rotation ratchet H in the ratchet ring J located in the block K. Located between the block K and the cylinder head block L is a valve box preferably in two sections, comprising the ring O and the cover piece P, having a shallow recess between them within which recess the valve Q is arranged. The back head R of the rock drill is of the usual construction and provided with the throttle valve S controlling the supply of pressure fluid to the machine. A sleeve T is preferably arranged over the rifle bar, and as shown, the valve Q has a hollow central portion or bore U encircling the rifle bar and sleeve T. This sleeve T is

held wholly within the head block L and cover piece P and centers the cover piece.

The section or ring O of the valve box preferably has a circular bore, and the plate valve Q is shown in this instance in the form of a circular comparatively thin oscillating disk tapering substantially uniformly from the median line or diameter V of the disk towards the periphery of each side. The valve oscillates on this median line, which forms the fulcrum in contact with the head block L. Sufficient clearance is provided between the valve and the valve box to permit the valve to oscillate freely and also permit pressure fluid to flow over the periphery of the valve. The valve is guided in any suitable manner as by means of the pins W extending into sockets X in the valve in which sufficient clearance is provided to permit oscillation. The cover piece P is provided with an annular flange P' concentric with the sleeve T and forming a stop for the valve. The cylinder head block L is provided with the inlet ports Y and Z controlled only by the valve, and the cylinder is provided with the free exhaust port a controlled only by the piston. A supply passage b connects the inlet port Z with the inlet port c at the forward end of the cylinder and the inlet port Y communicates directly with the rearward end of the cylinder. An inlet port d permits live pressure fluid to pass from the throttle valve S to the valve chest.

In the operation of the device, assuming that the piston B is moving rearwardly as indicated in Figure 1, the valve will be in the position as indicated and live pressure fluid is being admitted to the forward end of the cylinder. After the piston has passed beyond and uncovered the exhaust port a in the cylinder, the pressure in the forward end of the cylinder and underneath one end of the valve will have fallen or dropped while the opposite end of the valve is subjected to compression taking place in the rearward end of the cylinder, which will cause the valve to oscillate and close the inlet port Z and open the other inlet port Y to the rear end of the cylinder which will drive the piston forwardly.

The construction is simple, consumes a small amount of space, and permits a flat disk valve to be located around the rifle bar so that there are no protuberances on the

exterior of the cylinder. While the construction may be applied to any type of rock drill, the application is obviously particularly suitable for a stope drill.

5 We claim:

1. A fluid actuated rock drill comprising a cylinder and reciprocating piston, automatic rotation means for the drill steel including a rifle bar, a head block having a 10 valve seat portion, a valve box at the rear of the cylinder having a shallow recess forming a valve chamber, said valve box being provided with an annular flange forming a valve stop, and a fluid distributing 15 plate valve in said shallow recess in the form of a thin flat oscillating plate encircling the rifle bar, the valve being uniformly tapered from its median diameter towards the periphery at each side and bearing on 20 the seat portion of the head piece along said diameter to form a fulcrum.

2. A fluid actuated rock drill comprising a cylinder and reciprocating piston, automatic rotation means for the drill steel including a rifle bar, a free exhaust port located centrally of the cylinder and controlled only by the piston, a valve box having a shallow circular bore forming a valve 25 chamber located rearwardly of the cylinder 30 and in line therewith, said valve box being

provided with an annular flange forming a valve stop, a plate valve in the form of a thin flat oscillating circular disk in the said valve box recess and encircling the rifle bar, said disk tapering from the center towards each side, and inlet ports for the ends of the cylinder controlled only by said valve. 35

3. A fluid actuated rock drill comprising a cylinder and reciprocating piston, automatic rotation means for the drill steel including a rifle bar, a head block having a valve seat portion, a valve box at the rear of the cylinder having a shallow recess forming a valve chamber, said valve box being 40 provided with an annular flange forming a valve stop, a sleeve around the rifle bar, said sleeve being held wholly within the head block and valve box and acting to center the valve box, and a fluid distributing plate 45 valve in said valve box recess in the form of a thin flat oscillating disk encircling said sleeve, the fulcrum of said valve bearing directly on said valve seat portion of the head piece. 50 55

In testimony whereof we have signed this specification.

LEWIS C. BAYLES.
FRED M. SLATER.
